BY

Howard E. Larson
ATTORNEY

UNITED STATES PATENT OFFICE.

NILS G. LARSON, OF ATTLEBORO, MASSACHUSETTS.

VALVE-LIFTER.

1,380,654.

Specification of Letters Patent. Patented June 7, 1921.

Application filed February 19, 1920. Serial No. 360,015.

To all whom it may concern:

Be it known that I, NILS G. LARSON, a citizen of the United States, and resident of the city of Attleboro, in the county of 5 Bristol and State of Massachusetts, have invented certain new and useful Improvements in Valve-Lifters, of which the following is a specification.

This invention relates to so-called valve lifters of the type adapted to compress valve springs sufficiently to permit the stem pins to be readily extracted so that the valve may be freely removed; and the object of this invention is to provide such a device arranged 15 to engage either one or two valve spring members to raise the same and hold the springs under compression during the removing and repairing operations on the valve.

20 A further object of the invention is to so construct the device that it may be caused to engage and operate upon two adjacent valve springs simultaneously, and at the same time be so positioned as to permit free 25 and unobstructed operation upon the valve.

A still further object of the invention is that the lifter is adapted to raise or compress the springs in a straight line and so effectively prevent cramping the same or 30 displacing of the spring during the lifting operation.

With these and other objects in view, the invention consists of certain novel features of construction, as will be more fully described, and particularly pointed out in the appended claims.

In the accompanying drawings:

Figure 1 is a side elevation illustrating my improved lifter as applied to the valve 40 springs of an engine.

Fig. 2 is a perspective view showing the inner side of the fulcrum post.

Fig. 3 is a perspective view of the cam-lifting member.

45 Fig. 4 is a perspective view of the spring-engaging cross-bar member.

Fig. 5 is a perspective view of the fulcrum pin.

Fig. 6 is a side elevation illustrating the 50 complete device, showing the cross-bar and cam in full lines, as being in down position and in dotted lines in up or raised position.

With reference to the drawings, 10 designates the cross-bar member which is shown 55 as being of a length sufficient to engage two

adjacent valve springs, the same being cut out at 11 and 12 on one edge to fit around the valve stem 13.

The center portion of this bar is preferably bent or formed to extend upwardly providing two vertically-disposed side walls 14 spaced apart at 15 and connected at their upper ends by a bridge portion 16. Each of these side walls is slotted as at 17 to permit the passage of the pivot or guiding bolt or 60 pin 18 which is adapted to slide therein.

The fulcrum post 19 is preferably formed with a channel and is adapted to engage one of the side walls 14 of this cross bar to guide the vertical sliding motion of this bar, the 70 lower end 20 of this post being adapted to rest upon the cylinder block 21.

At the upper end of this post I have pivoted a cam member 22 which is also adapted to work in the space 15 between the vertical 75 side walls 14 of the cross-bar. This cam is pivoted by this fulcrum pin 18, its working edge being adapted to engage the under side of the saddle or bridge portion 16 of the bar, and this cam is provided with a handle 80 23 by the action of which the cross-bar may be raised and lowered.

The operation of the device is as follows:

When it is desired to operate upon two of 85 the valves it is only necessary to throw my cam handle down, place the fulcrum bar on the cylinder block, as illustrated in Fig. 1, and then pass the bar beneath the spring cups 24 of the springs 25, the upturned corners 26 of this bar serving as positioning stops. Then by lifting the handle from the position shown in full lines in Fig. 6 to the position shown in dotted lines in this figure, the edge of the cam 22 is caused to ride beneath the bridge 16 and raise the cross bar and the springs into the position illustrated in Fig. 1, in which position the stem pins 27 are released and adapted to be readily removed and so permit the valve to be taken 100 out for examination and repairs.

By the use of my improved device I am enabled to operate upon a single valve spring if desired without engaging both of the adjacent springs.

It will also be noted that by my improved device the lifting motion is in a direct or straight, vertical line and not on a curve or circle which is usually the case with the ordinary valve-lifting devices, thereby effect- 110

ually avoiding gripping or binding the stems and also displacing the springs; the device may lift into position and hold the springs compressed during the time that the 5 valves are being operated upon and repaired permitting them to be readily replaced as many times as desired and when finally in condition the stem pins may be positioned and the springs dropped into engagement 10 therewith without loss of time.

The foregoing description is directed solely toward the construction illustrated, but I desire it to be understood that I reserve the privilege of resorting to all the 15 mechanical changes to which the device is susceptible, the invention being defined and

limited only by the terms of the appended claims.

I claim:

1. A valve lifter having a fulcrum post, a 20 cam pivoted in said post, and a spring engaging member guided on said post and adapted to be operated by the movement of said cam to compress said spring.

2. A valve lifter comprising a fulcrum 25 post, a spring engaging cross-bar having an upwardly-extending portion guided on said post, a cam pivoted in said post and arranged to engage and lift said bar, and an operating handle on said cam.

In testimony whereof I affix my signature.

NILS G. LARSON.
